CLAIM

The ornamental design for a data processing monitor as shown and described.

DESCRIPTION

1. Data processing monitor

1.1 : Front perspective view

1.2 : Rear perspective view

1.3 : Front

1.4 : Rear

1.5 : Left

1.6 : Right

1.7 : Top

1.8 : Bottom

1.9 : Front perspective view in an alternate configuration of use

The even-dash broken lines depict portions of the data processing monitor that form no part of the claimed design. Reproduction 1.9 is a reference view, showing an alternate state of use.

1 Claim, 9 Drawing Sheets
